UNITED STATES PATENT OFFICE.

BENJAMIN F. RINDFLEISCH, OF CLEVELAND, OHIO, ASSIGNOR TO THE NATIONAL ACME COMPANY, OF CLEVELAND, OHIO, A CORPORATION OF OHIO.

COLLAPSIBLE TAP.

1,318,179.

Specification of Letters Patent.

Patented Oct. 7, 1919.

Application filed April 26, 1918. Serial No. 230,925.

To all whom it may concern:

Be it known that I, BENJAMIN F. RINDFLEISCH, a citizen of the United States, residing at Cleveland, in the county of Cuyahoga and State of Ohio, have invented certain new and useful Improvements in Collapsible Taps, of which the following is a specification.

This invention relates to improvements in taps, and more particularly to that class thereof known as collapsible taps, the object of the invention being to provide an improved tap of this character in which the cutters or chasers will be automatically released from the work after the tap has cut the required length, so that the tap may be removed from the work without the necessity of reversing or backing out of the threaded piece, and it is an improvement in part upon the collapsible taps shown and described in my Patent No. 1,214,954 dated February 6, 1917, in that a number of the parts therein required are dispensed with whereby the tap therein shown is very much simplified, and the expense of manufacture reduced.

In my prior structure, when the forward movement of the tap was stopped the chasers were released from the work by reason of the fact that the tap head or body was pulled forward from the shank or hub portion, which required a special form of coöperating locking means to maintain these parts in proper operative position.

In the present improvement, however, the tripping of the chasers or cutters so as to release them from the work, is not accomplished by pulling the tap head forward away from the shank or hub, but by shifting rearwardly by means of the work a shiftable member or sleeve, thereby to unlock the chasers and permit them to collapse, a structure which is very much simpler in construction and in operation and also for certain classes of work more efficient in results.

In the drawings accompanying and forming part of this specification, Figures 1, 2 and 3 illustrate side views of the assembled tap, Fig. 2 being taken at right angles to Fig. 1 and Fig. 1 illustrating the cutters in position to thread a piece of work, while Fig. 3 illustrates them in their collapsed position; Figs. 4, 5 and 6 are longitudinal

sectional views of this improved tap; Fig. 55 7 is a front end view of the tap; Figs. 8 and 9 illustrate front end views of the tap with the cover plate removed and showing different positions of the cutters; Fig. 10 is a front end view of the tap, the cover 60 plate, cutters and chasers removed; Fig. 11 is a cross sectional view taken on line 11—11 Fig. 1; Fig. 12 is a cross sectional view taken on line 12—12 Fig. 1; and Fig. 13 is a cross sectional view taken on line 13—13 65 Fig. 1.

Similar characters of reference indicate corresponding parts in the several figures of the drawings.

In the form shown in the drawings, this 70 improved tap comprises a body or head 2, of circular rod formation and of sufficient length to also form the shank 3 slabbed off at one side as at 4 for attachment thereof to the spindle or the tool-carrying turret 75 of the machine, in which machine the tap is usually reciprocated backward and forward to bring it into position to carry on its work and then carry it away from the work after the work is finished, and in 80 which the work or the tap is rotated for threading the piece. The body is drilled back as at 5 to receive the core piece or member 6, and the forward end of the body is provided with four radial slots 7 for the 85 reception of the cutters or chasers 8, each of which has its inner or under surface inclined or cam-formed for the purpose hereinafter described.

Located in the bore 5 of the body is the 90 core piece or member 6, made in the present instance in three sections 6', 6'' and 6'''. The core member proper 6' has that end thereof adjacent to the cutters provided with four curved or concaved sides 7 forming four cutter engaging corners or edges 8' and forwardly of the cutter engaging portions the core member is provided with a cylinder projection 9 adapted to extend through the cover plate 10. The rear end 95 of the core member is likewise provided with a projection 11 having an opening therein for the reception of one end of a coiled spring 6'', forming the second member of the core piece. The opposite end of the spring 6'' is received in an opening of a projection 12 carried by a short slabbed member 6''' forming the third member of 100 105

the core piece. These three parts 6', 6" and 6''' are assembled before they are slipped into the bore 5 of the body, and are held in position by a set screw 13 (see Fig. 4) engaging the slabbed-off portion of the member 6''''. After the core member is inserted in the bore it is by means of a wrench or by holding it in a vise given two or three turns thereby to wind up the spring 6" to the desired tension, it being held in that condition by the handle hereinafter described. The rear end of each cutter blade is provided with a V-shaped recess 14 for the reception of a tripping pin 15 located in a bore parallel with the bore 5 and pressed forward by a spring 16. Located on the body portion of the tap is a collar 17 having a pair of recesses 18. This collar is provided with an elongated slot 19, through which the handle 20 projects, and which handle extends into an opening of the core piece as at 21 (see Fig. 4). Carried by the collar at right angles to the handle is a pair of adjustable screws 22 for limiting the throw of the handle and thereby the movement of the chasers. In other words, by setting up these screws the desired amount, the chasers may be adjusted within certain limits to tap different sizes of holes. The collar 17, it will thus be seen, is loosely mounted upon the body of the tap by the handle projecting through it and into the core piece 6. Located in the rear of this collar for sliding movement upon the tap body is a sleeve 25. This sleeve is provided with a pair of forwardly projecting lugs 20' constituting with the recesses 18 of the collar the locking means for holding cutters in their adjusted or working positions. Located in recesses 27 of the tap body (see Fig. 4) and directly under the sleeve 25 is a pair of coiled springs. Projecting through the sleeve at diametrically opposite points and into these recesses for engagement with the forward ends of the springs 27 is a pair of screws 28, the springs thus acting to push the sleeve forward so that the locking lugs will engage in the recesses 18 of the collar at the proper time. The sleeve is provided with a pair of transversely extending slots 29, in which is located a pair of bars 30, the forward ends of which are secured to a disk 31 radially recessed as at 32 (see Figs. 7 to 10), whereby it may be readily slipped over the chasers. The bars 30 are at their rear ends secured to the sleeve 25 by headed bolts 33 and for this purpose they project through elongated slots 34 of the bars or arms 30 whereby the position of the disk 31 with relation to the sleeve may be adjusted, so that the position of the disk on the tap body may be adjusted so as to operate the sleeve and thereby trip the chasers or cutters according to the depth of the cut desired.

In assembling the tap, the core member 6 is, as hereinbefore stated, wound up so that the spring 6" will have the desired tension and then the handle is slipped through the collar and into the opening 21 in the core piece, thereby holding the spring under the tension given to it, and when the handle is shifted and the chasers locked in their set position, the coiled spring 6" is placed under still greater tension. When the chasers are released so as to collapse or return to their normal unset position, the coiled spring 6" throws the core piece 6 and the handle over until the handle hits the opposite side of the elongated slot 19, or one of the adjustable screws 22, according to the position in which it is set.

In operation, the handle is shifted to rotate or oscillate the core member 6, so that the corners thereof will force or project the cutters outwardly the desired distance. This shifting of the handle rotates or oscillates the collar therewith, so as to carry the recesses 18 of the collar in position to register with the projections or lugs 20' of the sleeve, whereupon the sleeve is forced forward by the springs 27 and thereby locks the collar and of course the core member in position to maintain the chasers in their set position. Thereupon the tap is fed forward in the usual way to engage and tap the work. When the piece of work has been completely tapped the disk 31 will come into engagement with the forward end of the work, so that the further forward movement of the tap operates to push back the disk and with it the sleeve 25 against the tension of its springs 27, so as to carry the locking projections or lugs 20' away from the recesses 18 of the collar, thereby releasing the collar, whereupon the spring 6" will rotate the core piece in the opposite direction to that in which it is rotated by the handle and carry the corners 8' from under the chasers, whereupon the spring-pressed tripping pins 15 will, by reason of the V-shaped recesses 14, force the cutters inwardly or collapse them in a manner which will be readily understood.

The adjustment of the set screws 22 with relation to the handle will determine the position of the corners of the core piece 6 with relation to the cam ends of the cutters, so that by this means the cutters may be adjusted within certain limits to engage smaller or larger pieces of work.

The various details may be more or less changed without departing from the spirit or scope of the claims, for instance it will be understood that where the tap carries three cutters or chasers or six cutters or chasers as is sometimes the case, the core member would then have the same number of curved or concave sides and corners. In other words the number of concave sides

and corners on the core member corresponds of course with the number of chasers that are used in the tap.

I claim as my invention:

- 5 1. A collapsible tap comprising a body having a plurality of radially shiftable cutters, a core member wound and held under tension for rotary movement relatively to the body for shifting the cutters, a coiled spring 70 connected directly to said core member for imparting rotary tension directly to said core member, and means for setting and locking said core member in position to maintain the cutters shifted outwardly.
- 10 2. A collapsible tap comprising a body having a plurality of radially shiftable cutters, a core member wound and held under tension for rotary movement relatively to the body for shifting the cutters, a coiled spring 75 connected directly to said core member for imparting rotary tension directly to said core member, means for setting the cutters, and means for locking said core member in position to maintain the cutters shifted outwardly and including means automatically operative on its engagement with the work to release said cutters to permit them to be collapsed. 80
- 15 3. A collapsible tap comprising a body having a plurality of radially shiftable cutters, a core member wound and held under tension for rotary movement relatively to the body for shifting the cutters, a coiled spring 85 connected directly to said core member for imparting rotary tension directly to said core member, means for setting the cutters, and means for locking said core member in position to maintain the cutters shifted outwardly and including means automatically operative on its engagement with the work to release said cutters to permit them to be collapsed and comprising a spring tensioned sliding sleeve carried by 90 the body, a rotatable collar also carried by the body and rotatable with the core, said collar and sleeve having coöperating locking means. 95
- 20 4. A collapsible tap comprising a body having a plurality of radially shiftable cutters, a core member wound and held under tension for rotary movement relatively to the body for shifting the cutters, a coiled spring 100 connected directly to said core member for imparting rotary tension directly to said core member, means for setting the cutters, and means for locking said core member in position to maintain the cutters shifted outwardly and including means automatically operative on its engagement with the work to release said cutters to permit them to be collapsed and comprising a spring tensioned sliding sleeve carried by 105 the body, a rotatable collar also carried by the body and rotatable with the core, said collar and sleeve having coöperating locking means. 110
- 25 5. A collapsible tap comprising a body having a plurality of radially shiftable cutters, a core member wound and held under tension for rotary movement relatively to the body for shifting the cutters, a coiled spring 115 connected directly to said core member for imparting rotary tension directly to said core member, means for setting and locking said core member in position to maintain the cutters shifted outwardly, and spring tensioned means located to engage the rear of the cutters for collapsing the cutters. 120
- 30 6. A collapsible tap comprising a body having a plurality of radially shiftable cutters, a core member wound and held under tension for rotary movement relatively to the body for shifting the cutters, a coiled spring 125 connected directly to said core member for imparting rotary tension directly to said core member, means for setting the cutters, and means for locking said core member in position to maintain the cutters shifted outwardly and including means automatically operative on its engagement with the work to release said cutters to permit them to be collapsed. 130
- 35 7. A collapsible tap comprising a body having a plurality of radially shiftable cutters, a core member wound and held under tension for rotary movement relatively to the body for shifting the cutters, a coiled spring connected directly to said core member for imparting rotary tension directly to said core member, means for setting the cutters, and means for locking said core member in position to maintain the cutters shifted outwardly and including means automatically operative on its engagement with the work to release said cutters to permit them to be collapsed and comprising a spring tensioned sliding sleeve carried by the body, a rotatable collar also carried by the body and rotatable with the core, said collar and sleeve having coöperating locking means. 140
- 40 8. A collapsible tap comprising a body having a plurality of radially shiftable cutters, each provided with a cam surface, spring tensioned means for collapsing the cutters, a core member wound and held under tension for rotary movement relatively to the body for shifting the cutters outwardly and comprising a member having a plurality of corners for engaging the cam-formed surfaces of the cutters, a coiled spring for imparting rotary tension to said core member, a collar located on said body and having an elongated slot, a handle projecting through said slot and into the core member for setting the core member, adjustable means carried at each side of said slot for engaging the handle, a spring tensioned sliding sleeve mounted on said body at the rear of said collar, said sleeve and collar having coöperating recesses and projections for locking the core member in position to maintain the cutters in working position, a sliding disk carried by the body in front of said collar and adjustably connected with the sleeve whereby when the disk engages the work the locking projec- 145
- 45 9. A collapsible tap comprising a body having a plurality of radially shiftable cutters, a core member wound and held under tension for rotary movement relatively to the body for shifting the cutters, a coiled spring connected directly to said core member for imparting rotary tension directly to said core member, means for setting and locking said core member in position to maintain the cutters shifted outwardly, and spring tensioned means located to engage the rear of the cutters for collapsing the cutters. 150
- 50 10. A collapsible tap comprising a body having a plurality of radially shiftable cutters, a core member wound and held under tension for rotary movement relatively to the body for shifting the cutters, a coiled spring 155 connected directly to said core member for imparting rotary tension directly to said core member, means for setting and locking said core member in position to maintain the cutters shifted outwardly, and spring tensioned means located to engage the rear of the cutters for collapsing the cutters. 160
- 55 11. A collapsible tap comprising a body having a plurality of radially shiftable cutters, a core member wound and held under tension for rotary movement relatively to the body for shifting the cutters, a coiled spring 165 connected directly to said core member for imparting rotary tension directly to said core member, means for setting and locking said core member in position to maintain the cutters shifted outwardly, and spring tensioned means located to engage the rear of the cutters for collapsing the cutters. 170
- 60 12. A collapsible tap comprising a body having a plurality of radially shiftable cutters, a core member wound and held under tension for rotary movement relatively to the body for shifting the cutters, a coiled spring 175 connected directly to said core member for imparting rotary tension directly to said core member, means for setting and locking said core member in position to maintain the cutters shifted outwardly, and spring tensioned means located to engage the rear of the cutters for collapsing the cutters. 180
- 65 13. A collapsible tap comprising a body having a plurality of radially shiftable cutters, a core member wound and held under tension for rotary movement relatively to the body for shifting the cutters, a coiled spring 185 connected directly to said core member for imparting rotary tension directly to said core member, means for setting and locking said core member in position to maintain the cutters shifted outwardly, and spring tensioned means located to engage the rear of the cutters for collapsing the cutters. 190

tions will be disengaged from the recesses and thereby the core member released to permit the cutters to be collapsed.

9. A collapsible tap comprising a body, a plurality of radially shiftable cutters carried thereby, a core member comprising a rotary cutter shiftable portion, a spring and a non-rotary portion securely held in said body, the cutter shifting portion of the core member being wound and held under tension for rotary movement relatively to the body for shifting the cutters, and means for setting and locking said core member in position to maintain the cutters shifted outwardly, said core member having a series of cutter engaging surfaces.

10. A collapsible tap comprising a body, a plurality of radially shiftable cutters carried thereby, a core member comprising a rotary cutter shiftable portion, a spring and a non-rotary portion securely held in said body, the cutter shifting portion of the core member being wound and held under tension for rotary movement relatively to the body for shifting the cutters, means for setting and locking said core member in position to maintain the cutters shifted outwardly, said core member having a series of cutter engaging surfaces, and said cutters having cam-formed surfaces.

11. A collapsible tap comprising a body, a plurality of radially shiftable cutters carried thereby, a core member comprising a rotary cutter shiftable portion, a spring and a non-rotary portion securely held in said body, the cutter shifting portion of the core member being wound and held under tension for rotary movement relatively to the body for shifting the cutters, means for setting and locking said core member in position to maintain the cutters shifted outwardly, said core member having a series of cutter engaging surfaces, said cutters having cam-formed surfaces, and sliding means operative on its engagement with the work for releasing said locking means.

12. A collapsible tap comprising a body having an axial bore therein and radial slots at its forward end, a plurality of radially shiftable cutters located in said slots, a core member located in said bore and wound and held under tension for rotary movement relatively to the body for shifting the cutters, a coiled spring located in said bore for imparting rotary tension directly to said core member, means for rotating the core member thereby to set the same, and means for locking said core member in its set position.

13. A collapsible tap comprising a body having an axial bore therein and radial slots at its forward end, a plurality of radially shiftable cutters located in said slots, a core member located in said bore and wound and held under tension for rotary movement

relatively to the body for shifting the cutters, a coiled spring located in said bore at the inner end of said rotary core member for imparting rotary tension directly to said core member, means for rotating the core member thereby to set the same, and means for locking said core member in its set position.

14. A collapsible tap comprising a body having an axial bore therein and radial slots at its forward end, a plurality of radially shiftable cutters located in said slots, a core member located in said bore and wound and held under tension for rotary movement relatively to the body for shifting the cutters, a coiled spring located in alinement with said core member for imparting rotary tension to said core member, means for rotating the core member thereby to set the same and comprising a rotary collar, a handle projecting therethrough directly into said core member whereby both are shiftable together, and means for locking said core member in its set position.

15. A collapsible tap comprising a body having an axial bore therein and radial slots at its forward end, a plurality of radially shiftable cutters located in said slots, a core member located in said bore and wound and held under tension for rotary movement relatively to the body for shifting the cutters, a coiled spring permanently held under rotary tension for imparting rotary tension directly to said core member, means for rotating the core member thereby to set the same, means for locking said core member in its set position and comprising a sliding sleeve located on the body, a spring located exteriorly of said bore for shifting said sleeve, a rotatable collar connected with said core member, said sleeve and collar carrying one lugs and the other recesses for locking the cutters, and means for shifting said sleeve against the tension of its spring to release the core member and thereby the cutters.

16. A collapsible tap comprising a body having an axial bore therein and radial slots at its forward end, a plurality of radially shiftable cutters located in said slots, a core member located in said bore and wound and held under tension for rotary movement relatively to the body for shifting the cutters, a coiled spring located in alinement with said core member for imparting rotary tension directly to said core member, means for rotating the core member thereby to set the same and comprising a rotary collar, a handle projecting therethrough directly into said core member whereby both are shiftable together, means for locking said core member in its set position and comprising a sliding sleeve located on the body, a spring located exteriorly of said bore for shifting said sleeve, said sleeve and collar

carrying one lugs and the other recesses, and means for shifting said sleeve against the tension of its spring thereby to release the core member and thereby the cutters.

- 5 17. A collapsible tap comprising a body having an axial bore therein and radial slots at its forward end, a plurality of radially shiftable cutters located in said slots, a core member located in said bore and wound 35 and held under tension for rotary movement relatively to the body for shifting the cutters, a coiled spring located in said bore for imparting rotary tension directly to said 40 core member, means for rotating the core member thereby to set the same and comprising a rotary collar, a handle projecting therethrough directly into said core member whereby both are shiftable together, means for locking said core member in its set 45 position and comprising a sliding sleeve located on the body, a spring located exteriorly of said bore for shifting said sleeve, said sleeve and core member carrying one lugs and the other recesses for locking the 50 cutters, and means for shifting said sleeve against the tension of its spring thereby to release the core member and thereby the cutters. 55
18. A collapsible tap comprising a body 55 having an axial bore therein and radial slots at its forward end, a plurality of radially shiftable cutters located in said 60

slots, a core member located in said bore and wound and held under tension for rotary movement relatively to the body for 35 shifting the cutters and comprising a rotary part and a fixed part, and a coiled spring also located in said bore between and connected to said rotary and fixed parts for directly imparting rotary tension to said 40 rotary core member part, means for rotating said rotary core member part thereby to set the cutters, means for locking the rotary core member part in its set position, and means for releasing the locking means. 45

19. A collapsible tap comprising a body having a plurality of radially shiftable cutters, a core member coöperating with the cutters to shift them, a spring normally wound up and in position to impart rotary 50 tension to said core member, said core member being at all times wound and permanently held in such wound condition under tension through the medium of said spring for rotary movement relatively to the 55 body for shifting the cutters, means for permanently holding the core member in such wound condition, and means for setting and locking said core member in position to maintain the cutters shifted outwardly. 60

Signed at Cleveland, county of Cuyahoga, and State of Ohio, this 22nd day of April, 1918.

BENJAMIN F. RINDFLEISCH.
